(57) **CLAIM**

The ornamental design for an adhesive dispenser/applicator device, as shown and described.

DESCRIPTION

FIG. 1 is a front/top perspective view of an adhesive dispenser/applicator device showing our design, the broken line showing of the hole defines the bounds of the claimed design but does not form part of the claimed design;

FIG. 2 is a left side elevational view of the design of FIG. 1, the right side is a mirror image;

FIG. 3 is a top plan view of the design of FIG. 1;

FIG. 4 bottom plan view of the design of FIG. 1;

FIG. 5 is a front end view of the design of FIG. 1;

FIG. 6 is a rear end view of the design of FIG. 1;

FIG. 7 is a front/top perspective view of a modified embodiment of the design shown in FIGS. 1 through 6, the broken line showing of the hole defines the bounds of the claimed design but does not form part of the claimed design;

FIG. 8 is a left side elevational view of the design of FIG. 7, the right side is a mirror image;

FIG. 9 is a top plan view of the design of FIG. 7;

FIG. 10 bottom plan view of the design of FIG. 7;

FIG. 11 is a front end view of the design of FIG. 7; and,

FIG. 12 is a rear end view of the design of FIG. 7.
